UNITED STATES PATENT OFFICE.

ORIEN STOTTS, OF PERRYTON, TEXAS, ASSIGNOR OF ONE-HALF TO JAMES A. JACKSON,
OF LIBERAL, KANSAS.

SLATTED BELT.

Application filed March 13, 1926. Serial No. 94,464.

This invention relates to slatted belts, and the object of the invention is the construction of a comparatively simple, yet efficient belt, provided with flights or cleats, and which belt may be used upon any kind of a machine, such as header-binders, combined harvesters and thrashers, and the like.

With the foregoing and other objects in view, my invention comprises certain novel combinations, constructions and arrangements of parts as will be hereinafter fully described, illustrated in the accompanying drawings, and more particularly pointed out in the appended claim.

15 In the drawings:

Figure 1 is a fragmentary, perspective view of my slatted belt, showing the same in an inverted position.

Figure 2 is a fragmentary, perspective view of the auxiliary section of the cleat.

Figure 3 is a fragmentary, perspective view of the primary section of the cleat.

Figure 4 is a sectional view taken on line 4—4, Figure 1.

25 Referring to the drawings by numerals, 1 designates the runner belts; these belts are preferably arranged in parallel position, and resting upon these belts, are the primary sections 2 of the cleats. The cleats extend 30 transversely of the runner belts 1 and the conveying belt 3. Near each end and the middle of the primary section 2, I preferably punch up the body of the cleat to form the rivet receiving apertures 4. Each section is 35 provided with an upstanding longitudinally extending rib 5, and this rib 5 fits into the rib 6 formed on the auxiliary cleat 7 when the parts are assembled, as shown in Figures 1 and 4. The primary sections 2 are laid 40 across the runner belts 1, then the conveying belt 3 is laid over sections 2, then the auxiliary sections are laid upon the conveying belt, so that the ribs 5 and 6 register. The auxiliary sections 7 are provided with apertures 8 that register with the apertures 4; these apertures 8 are larger than apertures 4, so that the upstanding edges of apertures 4 may extend partly into apertures 8, whereby the inner or lower heads of rivets 9 are 45 seated up in the sockets formed by the up-

wardly extending portions of the apertures 4, thereby decreasing the wear on the belt, by the rivets not hitting or pounding against the surface over which the runner belts travel during the operation of the belt. If the 55 lower heads of the rivets protruded, it would be only relatively a short time before they would be worn off, and the tendency would positively be to wear on the belt, as the heads came in contact with the supporting surface; 60 this is all eliminated by my improved structure as herein shown and described.

My sectional cleats are, of course, made out of sheet metal, and by reason of their rib structure, they serve to hold the material on the conveying belt, as the load can not "creep" far by reason of being stopped by the slatted or cleated structure of my belt.

Upon referring to Figure 4, it will be readily seen how portions of the runner belts 70 1 are held or pressed up into the sockets constituted by the apertures 4, with the lower heads of the rivets out of the way, in these sockets, for the smooth running of the belt, as well as the increasing of the life of the 75 same.

While I have described the preferred embodiment of my invention, and illustrated the same in the accompanying drawing, certain minor changes or alterations may appear to one skilled in the art to which this invention relates, during the extensive manufacture of the same, and I, therefore, reserve the right to make such changes or alterations as shall fairly fall within the scope of the 80 85 appended claim.

What I claim is:

As a new article of manufacture, a slatted belt comprising a series of parallel runner belts, a plurality of sectional cleats resting 90 upon and extending transversely of said runner belts, each sectional cleat including a primary and an auxiliary section, said primary section provided near its ends and middle with upwardly punched apertures, 95 constituting rivet receiving sockets, said auxiliary section provided near its ends and middle with comparatively large apertures registering with the apertures of the primary section, a conveying belt above said 100

runner belts and positioned between the primary and auxiliary sections of the cleats, and rivets extending through the runner belts and the conveying belt and the registering apertures of the sections of the cleats, holding parts of the runner belts up in the apertures of the primary sections of the

cleats, with the lower heads of the rivets seated up in the said receiving sockets in a plane above the outer face of the runner belts. 10

In testimony whereof I hereunto affix my signature.

ORIEN STOTTS.
